Atty.

UNITED STATES PATENT OFFICE.

CHARLES J. HIGGINS, OF HALLOWELL, MAINE.

TUBULAR LANTERN.

SPECIFICATION forming part of Letters Patent No. 392,430, dated November 6, 1888.

Application filed April 26, 1888. Serial No. 271,874. (No model.)

To all whom it may concern:

Be it known that I, CHARLES J. HIGGINS, a citizen of the United States, residing at Hallowell, in the county of Kennebec and State of Maine, have invented certain new and useful Improvements in Tubular Lanterns; and I do hereby declare the following to be a full, clear, and exact description of the invention, such as will enable others skilled in the art to which it appertains to make and use the same.

The invention herein disclosed consists of details of construction whereby the cone-plate and burner of a tubular lantern may be held securely in position, and yet capable of ready detachment, as will be hereinafter more fully described, and indicated in the claims.

Figure 1 is a view in elevation of a tubular lantern, parts being broken away to show the construction of the air-chamber. Fig. 2 is a view of the general form of construction heretofore used. Fig. 3 shows the position of the wick-raising shaft while the burner is being attached.

A represents a lantern, having the usual tubes, B, conveying air to an air-chamber beneath the cone-plate. This air-chamber is formed by a cylinder of sheet metal, C, slotted at its upper edge, and having near the same edge an exterior bead, c, which extends substantially around the cylinder. This cylinder is covered by a plate, D, carrying the cone B', and having a downwardly-projecting flange, d, with a slotted edge fitting over the cylinder, and having an internal groove, d', extending substantially around it, which groove engages with the bead on the cylinder and holds the cone-plate in position.

Heretofore there has been constructed a cylinder and cone-plate as in my device, which were held in position relatively to each other by diametrically-opposite projections or enlargements on the one and corresponding depressions in the other. The objection to this means of uniting the cylinder and cone-plate is that the projections and depressions, being of small extent, must necessarily be so long and deep, respectively, (in order to firmly secure the burner,) that the plate is not easily removable. By extending the groove and bead substantially around the plate and cylinder and slotting the edges of one or both, as at c' and d', said groove and bead may be very

slight, and yet operate to effectively prevent displacement of the cone-plate, and at the same time enable the operator to easily remove it. 55

In the construction of the burner, cone-plate, and cylinder heretofore used it has also been necessary (to keep the burner in its proper position) to provide said burner with a foraminous skirt or cone, H, Fig. 2, the upper edge 60 of which should form a bearing with the under side of the cone-plate D. This requires great nicety of construction in the manufacture of the parts, (for if the skirt were too high the cone could not shut down, while if too low the 65 burner would be loose and become displaced,) and therefore added to the cost of the whole, and also caused the position of the cone and burner to be dependent upon each other, so that not only a nice adjustment of them was 70 necessary when they were to be used, but also the removal of the cone at any time left the burner free, so that it was in danger of falling out, and, if lighted, of causing a conflagration. In my construction, however, the foraminous 75 skirt H, Fig. 2, is unnecessary, and therefore removed, and the burner and cone-plate are each secured independently of the other, thereby cheapening the cost of manufacture, making the lantern safer in use, and avoiding such 80 nice adjustment of the parts. The cylinder and cone-plate are provided with coincident slots or notches c' and d', through which passes the wick-raising shaft E' of the burner E.

Heretofore it has been impossible to screw 85 the burner into the top of the reservoir, for the reason that the wick-raising shaft lying in the notches prevented the turning of the burner. In order to obviate this difficulty and to permit the burner to be securely fastened in position, I make the wick-raising shaft in two parts, E' being the main part, which carries the ordinary wick-raising wheels, and E' a hinged extension of the shaft, which may be turned into the position shown in dotted lines, 90 Fig. 3, while the burner is being screwed into place, after which it is returned to its normal position in the notches, as shown by full lines. The joint of the shaft is formed at a point within the air-chamber, and said joint 95 thereby is not only protected, but also a bearing for the jointed shaft is provided at the point where said shaft passes through the wall of the air-chamber. It will thus be seen that 100

not only is the burner held firmly in position and in its proper relation to the cone, but also that the cone itself is always held in its proper position with respect to the perforation *g* in the foraminous plate *G*, which carries the globe *F*, which plate is itself guided, when raised or lowered, by the tubes *B*; also, that the foraminous plate, the cone, and the burner are independently supported and held in position and easily detachable when it becomes necessary to remove them.

The bead and groove, to which reference has been made, obviate the danger that the cone-plate and cone may be depressed at one side, and thus throw the slot of the cone out of coincidence with the burner-tube. A similar difficulty is obviated by the construction which permits the securing of the burner firmly in position.

20. The use of the bead and groove dispenses with the necessity of forming the cone-plate, as heretofore, with a shoulder to bear upon the upper edge of the cylinder.

Having fully described my invention, what I claim, and desire to secure by Letters Patent, is—

1. In a tubular lantern, a jointed wick-raising shaft, in combination with and having its joint inside the walls of the air-chamber, said walls being slotted.

2. In a tubular lantern, a burner-cone having a bead near its lower edge, in combination with the walls of the air-chamber, said air-chamber walls being also beaded near their upper edge, said cone having a notch or slot in its lower edge.

3. In a tubular lantern, a burner-cone having a bead near its lower edge, in combination with the walls of the air-chamber, said air-chamber walls being also beaded near their upper edge, said cone having a notch or slot in its lower edge, and said air-chamber wall being notched or slotted in its upper edge.

4. In a tubular lantern, a screw-burner and a jointed wick-raising shaft, in combination with an air-chamber composed of the top cone with a slot in its lower edge, and the air-chamber wall with a slot near its upper edge, for receiving and supporting said shaft and inclosing the joint thereof.

5. In a tubular lantern, a jointed wick-raising shaft having its joint inclosed and supported in operative position by the shell incasing it.

In testimony whereof I affix my signature in presence of two witnesses.

CHARLES J. HIGGINS.

Witnesses:

L. I. O'NEAL, A. P. STEWARD.
